UNITED STATES PATENT OFFICE.

LOUIS R. O'CONNOR, OF SEATTLE, WASHINGTON.

TOILET-SEAT COVER.

Application filed June 27, 1927. Serial No. 201,724.

This invention relates to improvements in individual toilet seat covers for comfort stations, or other toilets used by the general public, and aims primarily to provide a 5 toilet seat cover for effectively and properly protecting the user of the toilet and which is especially designed for automatic removal from the toilet seat by the flushing water after use. 10 Contemplated by the present invention is a sanitary toilet seat cover embodying a sheet of suitable flexible material arcuately and rectilinearly slitted to form and provide a rim, a central and forwardly disposed flap or tab, and curvilinear side flaps or tabs, one of said flaps having detachable connection with said rim and adapted to be severed therefrom when the toilet cover is to be used, all of which are important features and objects of the invention and are to be correlated in the broad aim of enhancing the efficiency of the device for general use. 15

The above, and additional objects which 20 will hereinafter be more specifically treated are attained by such means as are shown in the accompanying drawings, described in the following specification, and then more clearly pointed out in the claims, which are 25 appended hereto, and form part of this application.

With reference to the drawings, in which 30 there is illustrated several embodiments of the invention, and throughout the several views of which like characters of reference designate similar parts:

Figure 1 is a plan view of a toilet seat cover comprehended by the present invention, as it would appear prior to use.

40 Fig. 2 is a perspective view of the same, as it would appear when in use.

Beginning the more detailed description of the invention by reference to the drawings, the numeral 7 designates a rectangular sheet of relatively thin flexible material, such as paper or the like, which sheet is convergently slitted in symmetrical relation to its longitudinal axis, as indicated by the numeral 8, to form a forwardly and centrally disposed convergent bendable flap or tab 9, and which is arcuately and symmetrically slitted in opposed relation upon each side of said axis, as indicated by the numeral 10, to form a rim 11 and rearwardly disposed 45 bendable side flaps or tabs 12 having rectilinear inner edges and curvilinear outer 50 edges. The numeral 13 designates a series or line of perforations formed at the rear convergent terminal of the central flap 9, whereby the latter is rapidly and readily 55 separated or severed from the remainder of the sheet 7 by the user, when the cover is to be used, as will be manifest and apparent. The central flap 9 is permanently united at its base or forward end to the sheet 7 and is 60 flexed thereat to depend therefrom when the device is in use, while the side flaps 12 are also permanently united to the sheet 7 at their rear ends and are flexed thereat to 65 depend therefrom when the device is in use, 70 all as more clearly illustrated in Fig. 2.

In practice a supply of the toilet seat covers of the invention are stored in a suitable container adjacent the toilet, wherefrom they are readily and individually removed when required, whereupon the perforated connection of the flap or flaps with the remainder of the cover is severed, causing such flaps to drop. The user then places the cover upon the toilet seat with the flaps 75 of such cover depending or extending downwardly within the toilet bowl, so that when the toilet is flushed after use the swirling action of the flushing water within said bowl will exert a downward and inward pull upon the flaps hanging therein, which in turn exert a circumferential pull upon the rim of the correlated toilet seat cover portion of the same, to thereby loosen such portion 80 from the seat and draw the same inwardly 85 and downwardly into the bowl, wherefrom it is discharged with the flushing water into the drain pipe.

Manifestly, therefore, the devices of the invention will effectively and positively protect the users of public toilets against contracting disease therefrom, is extremely simple in construction, inexpensive to manufacture, convenient and sanitary in use, and is automatically removed from the toilet 95 seat after use by the flushing water without any manual actuation whatsoever.

While I have herein shown and described the invention with sufficient detail to enable those skilled in the art to understand the mode of construction and the principles involved, it is to be understood that there is no intentional limitation herein to the specific form and precise details of construction herein disclosed, except as expressly defined. 105 by the appended claims, and that various modifications of said construction may be 110

resorted to without departing from the invention, or the benefits derivable therefrom. I also desire to have it understood that certain features of the invention herein disclosed may be employed in other combinations than those shown and described.

Having thus fully described my invention, what I claim as new and desire to secure by Letters Patent is:—

- 10 1. A toilet seat cover embodying a sheet of flexible material slitted to provide a bendable central flap integral therewith at its forward end and detachably connected thereto at its rear end, and bendable side flaps integral at their rear ends with said sheet and equal in length to said central flap.
- 15 2. A toilet seat cover embodying a relatively thin sheet of flexible material symmetrically slitted upon each side of its longitudinal axis to provide a centrally and forwardly disposed bendable flap integral therewith at its forward end and detachably

connected thereto at its rear end, and arcuately slitted upon each side of said axis in opposed relation to provide bendable side flaps having curvilinear outer edges, said side flaps being integral at their rear ends with said sheet and equal in length to said central flap.

3. A toilet seat cover embodying a sheet of flexible material symmetrically and convergently slitted upon each side of its longitudinal axis to provide a bendable centrally and forwardly disposed convergent flap integral therewith at its forward end and 35 detachably connected thereto at its rear end, and arcuately slitted upon each side of said axis in opposed relation to provide bendable side flaps having curvilinear outer edges, said side flaps being integral at their rear 40 ends with said sheet and equal in length to said central flap.

In testimony whereof I affix my signature.

LOUIS R. O'CONNOR.
